[57] CLAIM

The ornamental design for a golfer's tool, as shown.

DESCRIPTION

FIG. 1 is a perspective view of a golfer's tool showing
my new design in an open position;

FIG. 2 is a bottom plan view thereof;

FIG. 3 is a front elevational view of a golfer's tool in a
closed position;

FIG. 4 is a top plan view thereof;

FIG. 5 is a bottom plan view thereof;

FIG. 6 is a rear elevational view thereof; and,

FIG. 7 is a right side elevational view, the left side being
a mirror image thereof.
